UNITED STATES PATENT OFFICE.

JOHN BATH, OF WORCESTER, MASSACHUSETTS.

WORK-DRIVING DEVICE.

Original application filed December 27, 1921, Serial No. 524,817. Divided and this application filed December 14, 1925. Serial No. 75,201.

This application is a division of my prior application Serial No. 524,817, filed December 27, 1921, and relates to a device for driving rotating work. While the device is capable of general application, it is particularly adapted for use in engine lathes, threading machines, thread grinding machines and other similar apparatus.

The general object of my invention is to provide a work driving device which is effective to turn the work in either direction, and to provide means by which the back-lash in the machine, on reversal, may be accurately determined and by which it may be taken up in the work driving device.

Fig. 1 is a sectional elevation of my work driving device, taken along the line 1—1 in Fig. 7;

Fig. 2 is a partial plan view looking in the direction of the arrow 2 in Fig. 1;

Figs. 3, 4, 5 and 6 are detail sectional views (taken respectively along the lines 3—3, 4—4, 5—5, 6—6, of Fig. 7);

Fig. 7 is an end elevation of the face plate and work driving attachments;

Fig. 8 is a plan view of certain parts of the machine, illustrating the means by which the amount of back lash is determined; and

Fig. 9 is an end elevation looking in the direction of the arrow 9 in Fig. 8.

I have shown my invention as applied to a thread grinding machine. My improved work driving device comprises a usual face plate 105 which is threaded on the end of a spindle 60 (Fig. 1) rotatable in a head stock 32. The plate 105 is provided with a hub or extension 106 on which is mounted a ring 107 supporting a pair of work driving dogs 108. These dogs are radially adjustable on the ring 107 and are secured thereto by binding screws 109. The inner ends of the dogs are shaped to receive and engage the shank of a tap or other article to be ground, which is held on the head and tail centers of the machine.

The ring 107 is flanged and is held against the face plate by an outer ring 110 secured to the face plate by binding screws 111 and 112 (Figs. 7 and 9). A slot 113 extends nearly around the ring 110 and the binding screw 111 is shown as extending through this slot, while the screw 112 extends through a hole in the ring 110 between the ends of the slot 113. A series of tapped holes 114 may be

provided in the face plate to receive the screws 111 and 112.

Segmental blocks 115 and 116 (Figs. 4 and 7) are provided with curved ribs or projections 117 (Fig. 5) fitting the segmental slot 113. These blocks are secured in angularly adjusted position by clamping bolts 118 and nuts 119 (Fig. 4). A spring handle 120 (Fig. 7) is secured to each block 115 or 116 and is provided with a spur 121 (Fig. 5) engaging notches 110^a (Figs. 7 and 9) formed at the outer edge of the ring 110.

A similar spring handle 122 (Fig. 9) is secured to the inner ring 107, this handle being provided with a socket or recess 123 adapted to receive pins or studs 124 formed on the ends of the bolts 118 which secure the blocks 115 and 116 in position. Stops 125 and 126 (Figs. 3 and 7) are also slidable in the slot 113 of the ring 110 and may be clamped in position as will be hereinafter described.

In the operation of my improved machine, the blocks 115 and 116 are so located that the movement of the handle 122 from one pin or stud 124 to the other will cause an angular movement of the dogs 108 exactly equal to the back lash in the connections between the work spindle and the grinding wheel table. The extent of this angular adjustment of the work required with a particular set-up of the machine is determined experimentally by use of the indicating device shown in Figs. 8 and 9.

An arm 130 (Fig. 8) is fixed on the wheel carriage (not shown) and extends forwardly and upwardly to a position for engagement by the short end of an index lever 131, pivoted at 132 on a stand 133. The stand is adjustably secured to the head stock 32 by a clamping bolt 134. A lock plate 135 is slidably mounted in guide-ways 136 on the head stock 32 and may be secured in adjusted position by a clamping bolt 137. An index or zero line is formed on one of the guide-ways 136 as a reference mark for the index lever 131.

In order to determine the exact amount of back lash in the connections between the spindle and the wheel carriage, the spindle is moved in the direction in which it has been rotating until the handle 122 of the dog-supporting ring 107 is aligned with the jaws of the lock plate 135. This plate is then advanced in its guide-ways 136 until it re-

leases the handle from the pin or stud 124 on which it has been seated and locks it from further angular movement. The stand 133 of the index lever or pointer 131 is then adjusted so that the rear end of the pointer will be pressed against the arm 130 by the pointer spring 138, while at the same time the end of the pointer co-incides with the zero mark on the guide-way 136.

10 The spindle 60 is then turned backward or in the opposite direction to that in which it has been rotating until the wheel carriage begins to move, such movement being instantly indicated by movement of the pointer 131. The second sliding block 115 or 116 is then moved to bring its stud 124 into alignment with the recess in the handle 122, in which position it is then secured.

20 With the positions of the blocks 115 and 116 thus accurately located, it is merely necessary to swing the handle 122 from one stud 124 to the other, when the direction of the table feed is reversed to cause the grinding wheel to accurately follow the thread in both directions of table feed. If it is found that the wheel when thus adjusted engages 25 slightly harder on one side than on the other, one of the blocks 115 or 116 may be further adjusted by moving its handle 120 one or 30 more notches along the ring 110.

When adjustment is once made for a particular set-up of the machine, no further attention is necessary beyond swinging the handle 122 from one stud 124 to the other at each end of the wheel travel. The output of the machine is thus greatly increased, as the usual idle return feed of the grinding wheel is entirely avoided.

35 When grinding certain types of thread, such as the Acme thread, it is sometimes desirable to feed the wheel sideways to widen the thread groove. The stops 125 are then used to preserve the original setting so that the slides 115 or 116 may be moved the required number of notches sideways to widen the thread and may then be returned to their original positions when a new thread is to be ground and widened.

40 The face plate 105 may be provided with graduations as shown in Fig. 2 and the ring 110 may have an index mark co-operating therewith to indicate the angular relation of these parts. These graduations are useful when it is desired to advance the ring 45 a certain angular amount relative to the face plate.

Having described the construction and 50 operation of my improved work driving device, it will be seen that I have provided a simple and effective means for accurately 55 determining the back lash in a machine, such as a thread grinding machine, and for taking up the work lash upon the reversal of

the machine, thus making the machine operative for many purposes on both forward and backward travel and eliminating the idle return stroke.

Having thus described my invention and the advantages thereof, I do not wish to be limited to the details herein disclosed otherwise than as set forth in the claims but what I claim is:—

1. In a thread grinding machine, a head stock, a work supporting spindle rotatable therein, a work driving member mounted thereon, and means on said head stock effective to release said member from said spindle and to hold said released member in fixed angular position.

2. In a thread grinding machine, a work 80 spindle, a face plate, a pair of driving dogs, a ring supporting said dogs, said ring being rotatably mounted on said plate, an arm on said ring, and a pair of locating devices angularly adjustable on said plate 85 and means to hold said devices in fixed relation to said plate after selective adjustment thereon, said devices thereafter co-operating with said arm to retain said ring and dogs in either one of two selected and definite angular positions.

3. In a thread grinding machine, a work spindle, a face plate, a pair of driving dogs, a ring supporting said dogs, said ring being rotatably mounted on said plate, and means 95 to adjust and secure said ring on said plate, said means including a spring arm on said ring and a toothed member secured to said face plate, the teeth of said member co-operating with said arm to determine the 100 position of said ring.

4. In a thread grinding machine, a work spindle, a face plate, a pair of driving dogs, a ring supporting said dogs, said ring being rotatably mounted on said plate, a pair 105 of locating blocks, spring arms on said ring and blocks, a member secured to said plate and having teeth engaged by said arms to position the same, and additional positioning devices on said blocks co-operating with 110 the arm on said ring.

5. A work driving device comprising a work spindle, a supporting member rotatable therewith, work engaging elements mounted on said supporting member, means 115 to simultaneously adjust all of said engaging elements angularly relative to said supporting member, means for limiting the angular adjustment of said engaging elements, means for positively fixing the limiting positions, and means to determine slight additional angular adjustments relative to said positive limiting means.

In testimony whereof I have hereunto affixed my signature.

JOHN BATH.
